CLAIM

The ornamental design for a rack for utensils or the like, substantially as shown and described.

DESCRIPTION

FIG. 1 is a top perspective view of the rack for utensils or the like showing our new design;
FIG. 2 is a top plan view thereof;
FIG. 3 is a side elevational view taken from the left of FIG. 1;
FIG. 4 is a front elevational view thereof;
FIG. 5 is a side elevational view taken from the right of FIG. 1;
FIG. 6 is a bottom plan view thereof;
FIG. 7 is a rear elevational view thereof.

FIG. 1

FIG. 2
